VANITY CASE

Otto Hallbauer, Grantwood, N. J., assignor of
one-half to Hans Bodenman, North Bergen,
N. J.

Application July 8, 1938, Serial No. 218,093

2 Claims. (Cl. 240—6.45)

This invention relates to improvements in vanity cases and has particular reference to illuminating means therefor.

An object of the invention is to provide an improved vanity case of simple and practical construction wherein an incandescent lamp is conveniently disposed for adjustment to operative position so as to illuminate a mirror, and mounted so that it can be readily removed and replaced.

Another object is to freely support a lamp socket for rocking movements to operative and inoperative positions, and to utilize the lid of the vanity case to restore the socket to its inoperative position when said lid is closed.

The above and other objects will appear more clearly from the following detailed description when taken in connection with the accompanying drawing which illustrates a preferred embodiment of the inventive idea.

In the drawing:—

Figure 1 is a perspective view of a vanity case constructed in accordance with the present invention, the lid thereof being shown open and the socket and its lamp in operative position.

Figure 2 is an enlarged plan view, partly broken away and shown in section, with the lamp in its inoperative position.

Figure 3 is a section on the line 3—3 of Fig. 2, the dotted lines indicating the operative position of the lamp, and,

Figure 4 is a transverse section on the line 4—4 of Fig. 3.

Referring more particularly to the accompanying drawing the vanity case is shown as comprising a housing or body 5 of rectangular formation to one end of which is connected the lid 6 carrying the mirror 7. The housing 5 is divided into front and rear compartments 8 and 9 by means of a partition 10. Said compartment 8 may contain a powder receptacle 11 having a closure 12 hinged at 13. The rear compartment 9 is closed by a cover plate 14 removably supported on the housing so that the same may be lifted from its position thereon when it is desired to gain access to the interior of the compartment 9. At the forward end of the cover plate 14 adjacent the partition 10, said plate is provided with a rouge receptacle 15 having a hinged cover 16. Rearwardly of said receptacle, the plate 14 is also provided with an opening 17 having a reduced forwardly extending portion 18, and in this opening there is rockingly supported a socket member 19 which carries a small incandescent lamp 20 disposed in juxtaposition to the portion 18 of

the opening for movement from an inoperative position below said plate 14 to an operative position slightly above the same as indicated by the full and dotted line positions of Fig. 3, the lamp being illuminated in the latter position as will appear in the course of the description.

The socket member 19 is oval in outline and is provided with a screwthreaded recess for receiving the lamp 20, and further has a contact 21 in its rear end by means of which current is supplied to the lamp in the operative position of the socket member. To removably maintain the socket member 19 in its position mainly within the compartment 9, but with its upper serrated surface 22 disposed above the plane of the cover plate 14 so that said surface may be engaged to rock the socket member, there is provided a support, generally indicated by the numeral 23, which preferably takes the form of a spring wire bent into U-shape with the intermediate portion of said wire secured in any preferred manner to the bottom of the receptacle 15, and with the side arms 24 of the support extending rearwardly on opposite sides of the socket member 19 so as to engage beneath the pivot pins 25 projecting from the ends of said member. The spring arms 24 thus exert a yielding upward pressure upon the socket member 19 which, being slightly larger than the main portion of the opening 17, will at all times contact the undersurface of the plate 14 and be thus frictionally maintained in position. Should it be desired to remove the socket member 19 for the purpose of replacing the lamp 20, the cover plate 14 need only be lifted and the socket member removed from its engagement with the spring arms 24 and thereafter replaced.

The compartment 9 of the housing is also utilized to contain two small dry cell batteries 26 disposed on opposite sides of the socket member 19, as seen in Fig. 4, with adjacent ends of said batteries engaging a contact strip 27 at the forward end of the compartment. At the rear end of the compartment there is also mounted a contact strip 28 engaged by a terminal of one of the batteries 26, and said contact strip 28 carries a curved terminal 29 disposed adjacent the bottom of the compartment and adapted to be engaged by the contact 21 only when the socket member 19 is rocked about its pivots 25 to the operative position of said member, as indicated by the dotted lines in Fig. 3. When said contact and terminal are thus engaged with each other a circuit is established for the lamp 20 to illuminate the same. With the lamp 20 in its operative position partially projecting above the plate 14, the lamp

- and its socket member are restored to inoperative position by a closing of the lid 6. When this occurs, the mirror 7 will contact the lamp 20 and force the same downwardly, thus rocking the socket 19 about its pivots 25 until said lamp is wholly depressed below the cover plate 14. A suitable spring catch 30 at the forward end of the housing 5 is utilized to engage the free end of the lid 6 to retain the same in its closed position.
- 5 10 What is claimed is:
1. In a vanity case, a housing having a top plate provided with an opening therein, a lamp-carrying socket of greater dimensions than said opening removably disposed within said housing
- 15 15 with a portion of said socket projecting through said opening, resilient means within said housing constituting a support for said socket and acting to frictionally maintain the latter in engagement

with edges of said opening, and means to light said lamp upon movement of said socket relative to said opening from one position to another.

2. In a vanity case, a housing having a top plate provided with an opening therein, a lamp-carrying socket of greater dimensions than said opening removably disposed within said housing with a portion of said socket projecting through said opening, said socket having pivots on opposite sides thereof, spring arms in said housing on 10 which said pivots freely rest and which constitute the sole support for said socket, said arms exerting a yielding pressure upon said socket to frictionally maintain the same in engagement with edges of said opening, and means to light said 15 lamp when said socket is moved to one position of adjustment relative to said plate.

OTTO HALLBAUER.
